CLAIM

The ornamental design for a hearing protection headset, as shown and described.

DESCRIPTION

FIG. 1 is a rear perspective view of a hearing protection headset showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a front perspective view thereof.

The broken lines shown in the drawings are only provided to illustrate the environment of the design, and form no part of the claimed design.

1 Claim, 7 Drawing Sheets(56)
